UNITED STATES PATENT OFFICE.

WILHELM KOLLE, OF FRANKFORT-ON-THE-MAIN, GERMANY, ASSIGNOR TO FARB-WERKE VORM. MEISTER LUCIUS & BRÜNING, OF HOCHST-ON-THE-MAIN, GERMANY, A CORPORATION OF GERMANY.

PROCESS OF PREPARING ARSENO COMPOUNDS WHICH ARE STABLE IN SOLUTION.

No Drawing.

Application filed January 12, 1922. Serial No. 528,836.

To all whom it may concern:

Be it known that I, WILHELM KOLLE, a citizen of Germany, residing at Frankfort-on-the-Main, Germany, have invented certain new and useful Improvements in a Process of Preparing Arseno Compounds Which Are Stable in Solution, of which the following is a specification.

I have found that by combining arseno-benzene derivatives, including the sulphoxylate compounds, with sulphoxylate-compounds of such amino-bodies as are not arsenobenzene derivatives stable arseno-compounds are obtained. In working out this invention I have made the remarkable observation that by combining such sulphoxylate compounds, as for instance those of the aminophenols and their alkylethers there are obtained particularly new biological effects. The biological modification consists in that the "dosis tolerata" of the mixture is considerably larger, and consequently its toxicity by far less as should be calculated according to the "dosis tolerata" of the components, without its therapeutical value being thereby materially reduced. Thus there has been found that when combining the sulphoxylate of 1 phenyl-p-arsenobenzene-5-pyrazolone-2.3-dimethyl-4-iminomethylene with the sulphoxylate of p-oxy-phenyleneiminomethylene (see Example 1), there was obtained as the tolerable dose not, as it should have been presumed, the average value of the respective dose of the components, but a "dosis tolerata" which was four times as large. Furthermore the surprising fact has been ascertained that in spite of the admixture of the sulphoxylate compounds free from arsenic, which have no action upon spirochaetæ, the approximately absolute quantity by weight necessary for the healing of one kilo of the animal's weight, remained nevertheless the same, while the therapeutical effect, calculated on the amount of arsenic, had increased four times as much. Of fundamental importance as a proof for realization of new unexpected chemotherapeutical effects by means of the above described preparations, is also the fact that when combining arsenobenzene derivatives which have almost no action at all upon trypanosomæ—

such as the sulphoxylate of 1-phenyl-p-arsenobenzene-5-pyrazolone-2.3-dimethyliminomethylene with a solution of the sulphoxylate of p-oxyphenyleneiminomethylene which has also no action upon trypanosomæ, the compounds thus obtained act upon trypanosomæ with a chemotherapeutical index of 1:3.

The combination of the compounds may be effected either by mixing them in a dry state or by combining solutions or suspensions therefrom with each other and then, if it is not preferred to use the solution thus obtained, removing the dissolving or suspending agent by evaporation.

Compounds of sulphoxylate of amino bodies may be obtained by briefly heating the amino - compound to 70-80° for instance o-aminophenol or urea with sodium formaldehydesulphoxylate (see Reinking, Dehnel und Labhardt, Ber. d. deutsch. chem. Ges. 38, 1069—1905—Binz und Marx, Ber. 43,2344—1910—). These compounds are easily soluble in water and unstable in air and they decolorize by reduction a solution of indigo carmin. With an iodine solution they may be titrated using four mol. of iodine on 1 mol. of sulphoxylate.

Examples.

1. A 10% solution of sulphoxylate of 4-arsenodi-1-phenyl-2.3-dimethylpyrazolone-4-4-iminomethylene-sulphoxylate (see British specification 146870 (dosis tolerata pro mouse-1/100 g.) is added to an equal volume of a 10% solution of sulphoxylate of 1-oxyphenylene - iminomethylene, $\text{H}_2\text{O.C}_6\text{H}_4\text{NH.CH}_2\text{OSO}_3\text{Na}$ (dosis tolerata=1/200g.). The dosis tolerata (tol.) of such a mixture is calculated, in case there has not been any chemical reaction of the components upon each other, generally as follows: The dosis tolerata may for instance be for one component $\text{tol.} = \frac{1}{a}$ and for the other component

$\text{tol.} = \frac{1}{b}$, $\frac{1}{a}$ and $\frac{1}{b}$ being grams figures. In this case $a. \text{tol.} = 1$; $b. \text{tol.} = 1$, consequently $(a+b) \text{ tol.} = 2$ and $\text{tol.} = \frac{2}{a+b}$, the dosis tolerata of the mixture being expressed in grams. Thus the theoretical figure is $\text{tol.} =$

1/150 g; in reality there has however been found by tests on animals tol.=1/40 g, that is to say a considerable diminution of toxicity.

5. Further examples are given in the following tabular statement, the last but one column containing the values for the dosis tolerata in each case, as it is calculated from the formula stated, the last column the values found by the tests on animals.

Ex- ample.	Arseno compounds.	Tol.	Components free from arsenic.	Tol.	Mixture of the components.	
					Tol. calcul.	Tol. found.
2.	1 ccm. of a 10% solution of the carbaminato of 4-arsenodi-1-phenyl 2,3-dimethyl-4-amino-5-pyrazolone and 1 ccm. of a 10% solution of bis-methyl-amino-tetraamino-arseno-benzene-carbaminato.	1/250	1 ccm. p - amino - phenolmethylene-sulphoxylate of 10% strength. NH.CH ₂ OSO ₃ Na.	1/200	1/250	1/5
3.	1 g. of hydrochloride of 4-arsenodi-1-phenyl 2,3-dimethyl-4-amino-5-pyrazolone precipitated with a solution of sodium carbonate.	1/250 1/300	1 g. p-amino-phenol with 1 g. of formaldehyde sulphoxylate Na condensed into HO-C ₆ H ₄ -NH-CH ₂ O ₃ Na.	1/200	1/225	1/100 1/150
4.	2 ccm. of a 5% solution of bis-methylamino-tetraamino-arseno-benzene-carbaminato.	1/300	0.5 ccm. p-amino - phenolmethylene sulphoxylate of 10% strength.	1/200	1/280 1/270	1/200 1/175
5.	1 g. of hydrochloride of 4-arsenodi-1-phenyl-2,3-dimethyl-4-amino-5-pyrazolone precipitated with a solution of sodium carbonate.	1/250	1 g. o-aminophenole with 1 g. formaldehyde-sulphoxylate Na condensed into NH.CH ₂ OSO ₃ Na.	1/200	1/225	1/50 1/75
6.	0.5 ccm. of a 10% solution of the carbaminato of 4'-arsenodi-1-phenyl, 2,3-dimethyl-4-amino 5-pyrazolone and 0.5 ccm. of a 10% solution of the sulphoxylate of the same compound.	1/250 1/100	0.5 ccm. o-amino-phenol-methylene sulphoxylate of 10% strength.	1/200	1/180	1/30
7.	2 ccm. 4,4'-dimethylamino-3,3, 5,5-tetraamino-arseno-benzene carbaminato of 5% strength.	1/300	1 ccm. p-anisidin-methylene-sulphoxylate of 10% strength. NH.CH ₂ OSO ₃ Na.	1/75	1/187	1/150
8.	2 ccm. 4,4'-dimethyl-amino-3,3, 5,5-tetraaminoarseno-benzene carbaminato of 5% strength.	1/300	1 ccm. o-anisidin-methylene-sulphoxylate of 10% strength. NH.CH ₂ OSO ₃ Na.	1/25	1/162	1/100
9.	1 ccm. of 4'-arsenodi-1-phenyl-2,3-dimethyl 5-pyrazolone-iminomethylene-sulphoxylate of 10% strength.	1/100	1 ccm. p-phenetidin-methylene-sulphoxylate of 10% strength. NH.CH ₂ OSO ₃ Na.	1/100	1/100	1/60
10.	2 ccm. of a 10% solution of the carbaminato of 4-arsenodi-1-phenyl 2,3-dimethyl-4-amino-5-pyrazolone.	1/250	0.5 ccm. ethylaminomethylene sulphoxylate of 10% strength.	1/75	1/215	1/75
11.	Like Example 10	1/250	0.5 ccm. ureamethylene-sulphoxylate of 10% strength.	1/25	1/205	1/60

Other biological experiments not stated above show that in spite of this diminution of toxicity the therapeutical value has remained almost unaltered, but that above all 5 the chemotherapeutical index has unexpectedly increased. Our invention therefore, constitutes a new and surprising achievement which could not be obtained by any of the hitherto known chemotherapeutical processes.

From these biological results may be concluded that there have been formed new chemical compounds from the arsenobenzene derivatives and the above described 15 sulphoxylate derivatives. The probability of this conclusion is strengthened by the fact that it is possible by adding the sulphoxylates to arsenobenzene derivatives which are insoluble in water for instance 20 4.4¹-dioxy-3.3¹-diaminoarsenobenzene and 4¹-arsenodi-1-phenyl-2.3-dimethyl-4-amino-5-pyrazolone-4 to render them soluble in water, as will be seen from the following examples.

25 12. 1 g. of p-aminophenol is subjected to condensation at 70-80° C. with 3 g. of formaldehydesulphoxylate in 3 ccm. of water. The resulting mass is diluted with water to 10 ccm. and there is added 1 g. of 30 sodium sal. of 4.4¹-dioxy-3.3¹ diaminoarsenobenzene dissolved in 10 ccm. of water. The precipitate thus obtained is dissolved with about 20 drops of $\frac{2}{n}$ caustic soda solution.

35 If carbon dioxide is then introduced no dioxydiaminoarsenobenzene is precipitated, a fact from which may be concluded that the base employed has entered into a new water-soluble compound.

40 13. 1 g. of the silver compound of 4.4¹-dioxy-3.3¹-diaminoarsenobenzene (British Patent No. 24,420/12) dissolved in 5 ccm. of water is precipitated by introducing carbon-dioxide. The precipitate dissolves in the course of about $\frac{1}{2}$ hour with a slight 45 alkaline reaction after adding the condensation product of 1 g. o-aminophenol and 1 g. of formaldehydesulphoxylate in 5.5 ccm. of water.

50 14. 5 g. of the silver compound mentioned in Example 12 dissolved in 25 ccm. of water are precipitated by introducing carbon dioxide. The precipitate dissolves in the course of about $\frac{1}{2}$ hour after adding the condensation product of 5 gr. of p-aminophenol and 5 g. of formaldehyde sulphoxylate in 25 ccm. of water.

55 15. 2 g. of hydrochloride of 4'-arsenodi-1-phenyl-2.3-dimethyl-4-amino-5-pyrazolone dissolved in 2 ccm. of water are mixed with

60 3 ccm. of $\frac{2}{n}$ caustic soda solution. To the base thus precipitated and suspended, there 65 is added a solution of sulphoxylate of p-

oxyphenylene - imino - methylene HO.C₆H₄. NH.CH₂OSONa produced by warming for a short time in the water bath 1 gr. of p-aminophenol with 1 g. of formaldehydesulphoxylate in 1.5 ccm. of water, adding 2 70 ccm. of $\frac{2}{n}$ caustic soda solution, filling up with water to 20 ccm. and filtering. The 4'-arsenodi-1-phenyl-2.3-dimethyl-4-amino-5-pyrazolone dissolves immediately. 75

16. 2 g. of hydrochloride of 4'-arsenodi-1-phenyl-2.3-dimethyl 4-amino-5-pyrazolone dissolved in 2 ccm. of water and precipitated by adding 3 ccm. of $\frac{2}{n}$ caustic soda solution 80 are mixed with a solution of sulphoxylate of o-oxyphenyleneiminomethylene produced by warming for a short time 1 g. of o-aminophenol with 1 g. of formaldehydesulphoxylate in 1.5 ccm. of water, adding 2 85 ccm. of $\frac{2}{n}$ caustic soda solution, filling up with water to 20 ccm. and filtering. The 4'-arsenodi-1-phenyl-2.3-dimethyl-4-amino-5-pyrazolone dissolves on being stirred for a short time. 90

17. 1 g. of the hydrochloride of 4'-arsenodi-1-phenyl-2.3-dimethyl-4-amino-5-pyrazolone dissolved in 1 ccm. of water and 95 precipitated by adding 1.5 ccm. of $\frac{2}{n}$ caustic soda solution are mixed with 1. g. of anthranilido - methylene - sulphoxylate dissolved in 2 ccm. of water and 2 ccm. of 100 $\frac{2}{n}$ caustic soda solution. The product dissolves on being stirred for a short time. 105

Claims:

1. The process of making arseno preparations which are stable in solution, which comprises combining arseno-benzene derivatives with sulphoxylate compounds of such amino bodies as are not arsenobenzene derivatives. 110

2. The process of making arseno preparations which are stable in solution by combining arsenobenzene derivatives with sulphoxylate compounds of such amino bodies as are not arsenobenzene derivatives, which comprises mixing said arsenobenzene derivatives with said amino bodies. 115

3. Process of making arseno preparations which are stable in solution, which comprises combining arsenobenzene derivatives with sulphoxylate compounds of such amino bodies as are not arsenobenzene derivatives in solution. 120

4. Process of making arseno preparations which are stable in solution, which comprises mixing solutions of arsenobenzene derivatives with solutions of sulphoxylate compounds of such amino bodies as are not arsenobenzene derivatives. 125

5. Process of making arseno preparations 130

which are stable in solution, which comprises, combining arsenobenzene derivatives with sulphoxylate compounds of such amino bodies as are not arsenobenzene derivatives in solution, and isolating the solid product from the dissolving agent.

6. As new products, the bodies obtainable by combining arsenobenzenes with sulphoxylate compounds of such amines as are not 10 arsenobenzenes, said bodies being readily soluble in water, more stable in solution than their components, their dosis tolerata being considerably larger than the calculated dosis tolerata of the components, and their therapeutic value being substantially as great as 15 the therapeutic value of the arsenobenzene component.

7. As new products, the bodies obtainable by combining arsenobenzenes with sulphoxylate compounds of such aminophenols as 20 are not arsenobenzenes, said bodies being readily soluble in water, more stable in solution than their components, their dosis tolerata being considerably larger and their toxicity considerably less than the calculated 25 dosis tolerata of the components, and their therapeutic value being substantially undiminished.

8. As new products, arsenobenzenes combined with sulphoxylate compounds of such 30 amino bodies as are not arsenobenzenes.

In testimony whereof, I affix my signature.

WILHELM KOLLE.
